UNITED STATES PATENT OFFICE.

HARRIET LYONS REDMOND, OF BOSTON, MASSACHUSETTS, ASSIGNOR TO THE
WILLIAM CARTER COMPANY, OF NEEDHAM HEIGHTS, MASSACHUSETTS, A
CORPORATION OF MASSACHUSETTS.

UNDERGARMENT.

1,414,202.

Specification of Letters Patent. Patented Apr. 25, 1922.

Application filed February 2, 1921. Serial No. 441,901.

To all whom it may concern:

Be it known that I, HARRIET LYONS REDMOND, a citizen of the United States, and a resident of Boston, in the county of Suffolk 5 and State of Massachusetts, have invented an Improvement in Undergarments, of which the following description, in connection with the accompanying drawings, is a specification, like characters on the drawings representing like parts.

This invention relates to undergarments and particularly to knitted undershirts for infants and children.

In order that the principle of the invention may be readily understood, I have disclosed a single embodiment thereof in the accompanying drawing wherein—

Fig. 1 is a front elevation of a garment constructed in accordance with my invention;

Fig. 2 is a vertical section upon the line 2—2 of Fig. 1;

Fig. 3 is a detail of the lower meeting ends of adjacent tapes; and

Fig. 4 is a side view or elevation of the garment, but representing the same as formed of a single piece.

The undergarment 1 is preferably a shirt, though my invention within its scope may 30 be embodied in a union undergarment. Desirably, however, the garment is a shirt of knitted material, the wales thereof running lengthwise or longitudinally of the fabric rather than transversely thereof. This renders the fabric highly elastic transversely. The garment may be formed of a single piece, being knitted as a tube, but I have herein represented the same as formed of two straight pieces seamed together along 35 the sides, as indicated at 2—2 in Fig. 1. The said garment is shown as provided with shoulder straps 3 which desirably are integral with the body of the garment, there being a suitable overseaming or some other 40 suitable formation along the upper and lower edges of the garment, as indicated at 4—4, and along the edges of the shoulder pieces, as indicated at 5—5, to prevent raveling. The garment thus far described is very 45 highly elastic.

The garment is provided with means for attaching a diaper or like member thereto. I am aware that it has heretofore been proposed broadly to employ a supporting tape

for this purpose, and I do not therefore 55 claim the same broadly. The structure herein disclosed, however, has been found in practice to be highly efficient and possesses certain advantages which I will point out hereinafter.

I provide a pair of tapes 6, 7 which are sewed or otherwise secured to the body along the edges 8—8 of the tapes by some 60 relatively elastic stitch. The tapes 6, 7 are themselves preferably of knitted material, 65 the wales thereof extending longitudinally of the fabric. If desired the said tapes may be of slightly less elasticity than the body 1. I have found that superimposing a somewhat 70 elastic tape and securing it to the elastic body 1 results in a structure wherein the component parts are not liable to be torn apart or to pull unduly upon each other, because of materially different degrees of elasticity. The said tapes 6, 7 at front and back 75 are continued down about to the point indicated and are at the lower ends positioned parallel, as indicated at 9, 10, and as shown more in detail in Fig. 3, their tips are folded transversely upon themselves, so as to 80 provide tabs to which a diaper or napkin may be pinned or otherwise secured. If desired and as shown, at the front of the garment the tapes 6, 7 may at their lower ends be united at their meeting edges, 85 so as to form a single tab 9, and the same structure may be employed at the back, thus forming a single tab 10 at the back, or if desired the tapes 6, 7 may be so 90 cut from the material from which they are made that a single wide tab 9 is presented at the front, and a single wide tab 10 at the back, the said tabs being integral from the outer edge of the tape 6 to the outer edge of the tape 7. The said tabs are 95 adapted to receive a safety pin or other attaching device for the diaper or napkin. If desired, the tapes 6, 7 may extend entirely over the shoulders of the garment overlying the shoulder pieces 5, 5, but in certain cases 100 I have found that this makes too heavy or solid a construction, and in those cases I preferably terminate the garment 1 along the lines of its upper edge 4, and employ the upper parts of the tapes 6, 7 as shoulder straps. In this way, the shoulder pieces are 105 themselves of a single thickness, and yet are preferably elastic, because desirably the

tapes 6, 7 are themselves formed of knitted or other sufficiently elastic material.

If the wales of the knitted body 1 extend longitudinally of the garment, then desirably the wales of the tapes 6, 7, when knitted extend in the same direction. Conversely if the wales of the knitted body 1 extend transversely of the garment, then the wales of the tapes 6, 7 would extend desirably transversely of the garment.

Desirably the shoulder pieces 5, 5, if employed, and the portions of the tapes 6, 7, extending over the shoulders, are formed with longer inner edges than outer edges, as shown, so that they conform substantially to the slope of the shoulders and do not tend to slide or slip from place.

In addition to the tapes 6, 7, I may and preferably do provide tapes 11, 12, preferably of knitted material like the tapes 6, 7, and having lower ends providing tabs 13, 14 preferably like the tabs 9, 10 and constituting means whereby stockings or other parts may be secured. The said tapes 11, 12 desirably extend down both the front and back of the garment at the inclination represented in Fig. 1, as shown more clearly in Fig. 4, so that at the lower ends the front and back portions of the tapes meet to form the said tabs 13, 14, which are thus positioned at the sides of the garment, in convenient position for receiving the upper ends of stockings or other parts. Desirably and as clearly shown in Fig. 1, the tapes 6, 7, 12, 13 conform in position and shape to the described shape of the shoulder pieces 5, 5, thus cooperating therewith to cause said shoulder pieces to cling in place.

It is not essential that all the tapes extend over the shoulders, and if desired either the tapes 6, 7 or the tapes 11, 12 may terminate at the upper edge of the garment.

Having thus described one illustrative embodiment of my invention, I desire it to be understood that although specific terms are employed, they are used in a generic and descriptive sense and not for purposes of limitation, the scope of the invention being set forth in the following claims.

Claims.

1. A knitted undergarment having knitted tapes secured to the outer face thereof and extending substantially lengthwise of the garment, the wales of the garment and the wales of the tapes all extending longitudinally of the garment, whereby the garment and the tapes stretch substantially evenly and without tendency of being torn apart, said knitted tapes having their lower ends extending in parallelism without superposition but in proximity and having their tips folded upon themselves, thereby to provide integral reinforced elastic terminal tabs protruding from the garment for the attachment of a diaper or the like.

2. A knitted undergarment having the wales thereof extending longitudinally and having shoulder pieces, said garment having attached to the outer face thereof knitted front and rear tapes 6, 7, and knitted side tapes 11, 12, whereof the wales extend longitudinally, at least one of said tapes extending over each shoulder piece, said front and rear tapes and said side tapes having their lower ends extending in parallelism and in proximity but without superposition and having their tips folded transversely upon themselves, thereby to provide integral elastic terminal tabs 9, 10, 13, 14, protruding at front, rear and sides of the garment respectively.

In testimony whereof, I have signed my name to this specification.

HARRIET LYONS REDMOND.
